BICYCLE FRAME

Charles Patrick Duncan Davidson, Droitwich, England,
assignor to Joseph Lucas Limited, Birmingham, Eng-
land

Filed July 15, 1975, Ser. No. 596,286

Claims priority, application Great Britain Jan. 18, 1975

Term of patent 14 years

Int. Cl. D12—II

U.S. Cl. D12—111

FIG. 2.

FIG. 4

FIG. 1

FIG. 5

FIG. 3

FIG. 1 is a side elevational view of a bicycle frame showing my new design, the opposite side being a mirror image thereof;

FIG. 2 is a bottom plan view thereof;

FIG. 3 is a top plan view thereof;

FIG. 4 is a front elevational view thereof; and

FIG. 5 is a rear elevational view thereof.

I claim:

The ornamental design for a bicycle frame, as shown.
